PORTABLE AIR FILTRATION UNIT

James V. Knab, Grand Rapids, Mich., assignor to Weber Showcase & Fixture Co., Div. of Walter Kidde & Company, Inc., Grand Rapids, Mich., a corporation of New York

Filed Dec. 18, 1967, Ser. No. 9,813

Term of patent 14 years

Int. Cl. D23—04

U.S. Cl. D23—149

FIG. 2.

FIG. 1.

FIG. 4.

FIG. 3.

FIG. 1 is a side-elevational view of the portable air filtration unit embodying my new design;

FIG. 2 is a front-elevational view thereof;

FIG. 3 is a side-elevational view of the side thereof opposite from that illustrated in FIG. 1; and

FIG. 4 is a rear-elevational view thereof.

I claim:

The ornamental design for a portable air filtration unit, substantially as shown and described.
